Attorney, Agent, or Firm—Darby & Darby

[57] CLAIM

The ornamental design for a lavatory handle, as shown and described.

DESCRIPTION

FIG. 1 is a perspective view taken from the top, front and left side of a lavatory handle showing my new design;

FIG. 2 is a top plan view thereof;

FIG. 3 is a left side elevational view thereof;

FIG. 4 is a right side elevational view thereof;

FIG. 5 is a front elevational view thereof, the rear view being a mirror image of the front view shown; and

FIG. 6 is a bottom plan view.

FIG. 1

FIG. 5

FIG. 2

FIG. 6

FIG. 3

FIG. 4
